UNITED STATES PATENT OFFICE.

CHARLES F. A. HINRICHES, OF BROOKLYN, NEW YORK.

DESIGN FOR A LAMP.

SPECIFICATION forming part of Design No. 12,131, dated January 18, 1881.

Application filed October 21, 1880. Term of patent 7 years.

To all whom it may concern:

Be it known that I, CHARLES F. A. HINRICHES, of the city of Brooklyn, county of Kings and State of New York, have invented or produced a Design for a Lamp Standard and Reservoir, of which the following is a description.

The standard and fountain are represented in the annexed drawing.

10 The bottom *a* of the standard may be round, square, or polygonal, and does not form a necessary part of this design.

15 There is a foot-piece to the lamp-standard, composed of a ring, *b*, resting upon the base *a*, said ring having its surface ornamented by an undulating band. The base *c* has a band, *d*, around its smallest portion, and its surface ornamented with leaflets, as represented. The standard or column *e* is tapering and enlarged 20 near its base, and has curvilinear surfaces, as represented.

The top of the standard is ornamented with coves *f g h* and bands *i k l*, as shown.

25 The arms *m n* are square in cross-section and zigzag, as shown. At the outer ends are the burners *o o*, and the inner ends are attached to a coupling-block, *p*, at the upper part of the standard, and there are conical ornaments *q* near the junction of the block and arms.

30 The shade-rings are provided with open millions *s*, between the under edge and the vertical supports.

The ornamental design of the reservoir consists in an elliptical vase-shaped body, *t*, resting upon a base, *u*, with bands and leaflet ornaments, and at the top there is a cap or cover, *v*, having a coronated edge and conoid center, with a knob, *w*.

This design, as a whole, is highly ornamental and unique, but some portions might be 35 separated for use in hanging and other lamps.

The body portions of the reservoir and standard will usually be of vitrified material, having upon them leaves and other ornaments.

I claim as my invention—

45 1. The design for a lamp-standard, consisting of the tapering portion *e*, enlarged at the lower part and having the curved configuration, the ring *b* and base *c*, substantially as shown.

50 2. The design for a lamp-standard, consisting of the coves and bands at the top of the standard, the arms *m n*, and ornaments *q*, substantially as described and shown.

3. The design for a lamp-fountain, consisting of the elliptical body *t* and base *u*, and the cap or cover *v*, substantially as shown.

55 Signed by me this 15th day of October, A. D. 1880.

C. F. A. HINRICHES.

Witnesses:

GEO. T. PINCKNEY,
WILLIAM G. MOTT.
